UNITED STATES PATENT OFFICE.

WILLIAM H. LUDEN, OF READING, PENNSYLVANIA.

COUNTING AND PACKAGING MECHANISM.

1,237,351.

Specification of Letters Patent. Patented Aug. 21, 1917.

Application filed March 21, 1917. Serial No. 156,517.

To all whom it may concern:

Be it known that I, WILLIAM H. LUDEN, a citizen of the United States, residing at Reading, in the county of Berks and State 5 of Pennsylvania, have invented certain new and useful Improvements in Counting and Packaging Mechanism, of which the following is a specification.

My invention relates to mechanism adapted particularly for counting and packaging small articles such as cough drops, pills, or the like; and it consists in the improved construction employing a cross wise passage-way for the packages, in connection with a 10 longitudinally movable delivery slide, hereinafter fully described in connection with the accompanying drawings and the novel features of which are pointed out in the claims.

20 Figure 1 is a plan view of a simple mechanism embodying the essential features of my invention; the two part tray shown being partly broken away.

Fig. 2 is a longitudinal section of the same 25 on the line 2—2 of Fig. 1; and Fig. 3 a cross section on the line 3—3 of Fig. 2.

Fig. 4 is a separate plan view of the two-part tray, the delivery slide portion being shown moved laterally to uncover the bottom portion.

Figs. 5 and 6 are respectively cross sectional views, on the lines 5—5 and 6—6 of Fig. 4, of the delivery slide, and bottom portion, of the two part tray.

35 As shown in the drawings the table is made up of two side frames 10, 10 spaced by cross bars 11, 11, 11, and mounted on legs 12, 12. A transverse package passage-way 13 is formed intermediate the length of 40 the table by spaced cross bars 14 and 15, and the side frames are cut away at 16, 16 in line with said way 13 for a passing row of cartons as hereinafter described. A depressed tray slide-way is formed between 45 the side frames 10, 10 to one side of this passage-way 13, by bottom bars 17, 17, 17, 17, supported on two of the cross bars 11, 11, as shown, the cross bar 14 forming an end stop. This slide-way is open at the end opposite the cross bar 14 for entering and with 50 drawing a two-part tray herein later described. On the other side of said passage-way 13, a series of recesses 18, 18, etc., are

provided, spaced by partitions 19, 19, etc., and each formed with a filleted end 20 rising to the top of the cross bar 15 as shown. A wire netting 21 extends from these recesses to the end cross bar 11, and side stops 22, 22, arranged parallel with the frame 10, 10, form a slide-way of reduced width for 60 the delivery-slide of said two-part tray described later herein.

Supported beneath the passage-way 13, on bars 23, connecting the legs 12, 12, is a platform 25, forming the bottom member 65 of the carton passage-way. This platform extends beyond the table on both sides for facilitating the feeding and removing of cartons, and is provided with side guides 26, 27, as shown, in alignment with the bars 14 70 and 15. These side guides are elevated above the platform 25 by angle braces 28 so as to expose the carton above and below them. A tray 30 to catch small discarded particles is shown supported below the platform 25. A spaced stop 31 is provided between the side stops 22, 22 of the reduced 75 slide-way for the delivery slide portion of the tray, and the bar 14 is beveled, as shown at 32.

The cartons 35, are set upon a portion of the platform 25 extended beyond the table, and supported thereon by the side guides 26, 27 with their upper ends open to receive articles to be packaged therein. They are 85 intermittently fed along said platform through the passage-way 13 as shown, and the filled cartons are then removed from the opposite extended portions of the platform. These cartons may be fed to the platform 90 25 by hand or directly from a machine that sets them up, and at the delivery end may also be run directly to a top-closing device, neither of which form a part of the present invention.

95 The two-part tray for delivering the articles to the cartons consists, as shown particularly in Figs. 4, 5 and 6, of a bottom portion 40, having grooved sides 41 and 42 forming a guide-way for the delivery-tray portion 100 43. The bottom tray portion 40 is preferably formed with a metal surface as shown, and is provided with perforations 44 for the passage of small or broken portions of the articles. It is also provided along one side 105 with an inclined scoop-edge 45 for dipping

into a bin if desired; this edge, as shown, extending from one of the grooved sides 42. The delivery slide portion 43 is of a thickness about equal to the article to be packaged and is provided with rows of openings 48, 48, etc. extending lengthwise thereof. These openings conform in shape, as shown, to the shape of the article to be packaged, and the number of longitudinal rows determine the numbers of cartons that can be filled at one movement of the slide, while the number of openings in each row determine the maximum number of articles that can be delivered at one reciprocating movement of the slide. A handle 46 is provided to reciprocatively move this slide.

This two part tray 40-43 is adapted to slide upon the bottom bars 17, 17, 17, 17 between the side frames 10, 10, until it comes 20 against the stop 14. This stop is of a height not greater than the thickness of the bottom portion 40 of the tray, as shown, so as to prevent further sliding movement of said bottom portion, but permitting the delivery portion 43 of the tray to pass over said stop into the reduced width slideway formed between the strips 22, 22. The movement of this delivery portion 43 is limited by the stop 31.

30 This two part tray is filled with articles, as by dipping in a bin and shaking off all surplus articles that do not fill the rows of openings 48, or it may be done by other means not shown. Each opening 48 carries 35 only one of the articles to be packaged, and when the delivery-slide is in withdrawn position within the grooved sides 41 and 42, the bottom 40 forms a support to retain the articles in the grooves. When the delivery 40 slide is moved across the passage-way 13 however, the articles will fall into the row 45 of cartons supported therein on the platform 25, the beveled edge 32 assisting in the delivery. Should any of the articles fail to immediately fall into this passage-way, they will fall into one of the recesses 18, which will indicate the carton that failed to receive its full count, and can be quickly moved up the filleted end 20 into the proper 50 carton. The perforations 44, spaced slide bars 17, 17, 17, 17, and wire netting 21, permit the passage of broken particles to be caught by the tray 30.

The cartons are fed along the passage-way 55 13, transversely of the tray slide movements, in a step-by-step movement. Ten rows of openings 48 are shown, so that ten cartons at a time are moved into the passage-way 13 for each reciprocal movement of the delivery-slide 43. This number, may of course be varied and the number of aligned openings in each row, twenty as shown, may be varied, either by adjustment of the stop 31, covering up certain ones, or omitting

them altogether from the slide. The side 65 guides 26 and 27 of the platform 25 are spaced above the latter as stated, so as to permit sight and adjustment of the passing row of cartons.

What I claim is:—

1. In a counting and packaging mechanism, a table having a transverse package passage-way, and a delivery slide on said table movable across said passage-way and provided with a longitudinal series of carrier perforations.

2. In a counting and packaging mechanism, a table having a transverse passage-way adapted to receive a determined number of packages, and a delivery slide on said table movable across said passage-way and provided with carrier perforations arranged in corresponding longitudinal series.

3. In a counting and packaging mechanism, a table having a transverse package passage-way, and a removable tray comprising a bottom portion fixedly supportable on said table and a delivery slide movable across said passage-way and provided with a longitudinal series of carrier perforations.

4. In a counting and packaging mechanism, a table having a transverse package passage-way adapted to receive a determined number of packages, and a removable tray comprising a bottom portion fixedly supportable on said table and a delivery slide movable across said passage-way and provided with carrier perforations arranged in corresponding longitudinal series.

5. In a counting and packaging mechanism comprising a longitudinally movable delivery slide having a longitudinal series of carrier perforations; a supporting table therefor having a transverse package passage-way and a longitudinal surface recess providing communication between said perforations and said passage-way.

6. In a counting and packaging mechanism comprising a longitudinally movable delivery slide having parallel longitudinal series of carrier perforations; a supporting table therefor having a transverse package passage-way adapted to receive a determined number of packages and a corresponding number of longitudinal surface recesses each arranged to provide communication between said passage-way and a determined one of said series of perforations.

7. In a counting and packaging mechanism, a table having a transverse package passage-way adapted to receive a determined number of packages, and a removable tray comprising a bottom portion fixedly supportable on said table and a delivery slide movable across said passage-way and provided with carrier perforations arranged in corresponding longitudinal series; said bottom portion having a scooping-edge arranged at right

angles to the movement of said delivery slide.

8. In a counting and packaging mechanism, a table having a transverse passage-way adapted to receive a determined number of packages, and a removable tray comprising a bottom portion fixedly supportable on said table and a delivery slide movable

across said passage-way and provided with carrier perforations arranged in corresponding longitudinal series; said table being provided with a stop adapted to limit the movement of said delivery slide. 10

In testimony whereof I affix my signature.

WILLIAM H. LUDEN.
